UNITED STATES PATENT OFFICE

DAVID E. EVANS, OF COLUMBUS, OHIO, ASSIGNOR TO THE COLUMBUS DENTAL MANUFACTURING COMPANY, OF COLUMBUS, OHIO, A CORPORATION

CARDING DEVICE FOR ARTIFICIAL TEETH

Application filed October 18, 1930. Serial No. 489,675.

Heretofore artificial teeth have been mounted on a card or the like, formed of cardboard, metal or wood in combination with wax or other penetrable material, or having a coating of such material thereon, the teeth being pressed into the wax and being held thereby on the card. This method of mounting the teeth is not satisfactory in warm weather, the wax becomes too soft and easily soils the teeth, and, in cold weather, it becomes too hard and the teeth do not properly adhere.

Another method employed for supporting or mounting teeth consists of a mount of cardboard, wood or metal, having split metal pins.

Another method consists of a mount having spring metal flanges or lugs. These last two methods are unsatisfactory because parties in removing the teeth from the mount pull the teeth transversely of the flanges or lugs in removing them, instead of sliding them off in the plane of the long axis of the flanges or lugs, which results in the metal flanges or lugs chipping the teeth when they are thus removed.

The object of my invention is to provide a mount or card device for artificial teeth, which is substantially rigid in construction and will not easily bend or break.

A further object of my invention is to provide such a mount which will not soil the teeth.

A further object of my invention is to provide a mount for teeth which will eliminate chipping of the teeth when the teeth are removed from the mount.

In the drawings:

Figure 1 is a front elevation of my improved mount card for artificial teeth.

Figure 2 is a view of the blank for the mount with the retention device attached.

Figure 2a is an end elevation of Figure 2.

Figure 3 is a longitudinal sectional view

through the mount on the line 5, Figure 2, with the retention device removed.

Figure 4 is a top plan view of the retention member detached.

Figure 5 is a true sectional view on the line 5—5 Figure 2.

Figure 6 is a rear elevation of the mount.

Figure 7 is a transverse sectional view of the mount partially folded.

Figure 8 is a sectional view on the line 8—8 Figure 1.

Figure 9 is a view similar to Figure 8 with a tooth mounted on the mount card.

The reference letter A designates the blank of my improved tooth mount which is designated to be bent upon itself on the dotted line B, as clearly seen in Figures 7, 8, and 9, is formed with a boss C on its outer or obverse face and a resultant depression or groove D in its inner or reverse face. The blank is provided with openings 11 hereinafter referred to. Near the upper edge of the blank slots 12 are punched through the blank in the boss C, which slots open through the outer face of the boss and intersect the groove D, while the side edges of the blank near the bottom are notched as at 13.

The tooth retention strip 14 is formed from a suitable non-metallic material which is crimped at predetermined intervals throughout its length to form lugs 15. The strip 14 is laid in the groove D in the rear face of the blank A, and the lugs 15 are forced by a suitable instrument through the slots 12, as clearly shown in Figure 5. It will be noted, as shown in Figure 5, that these lugs 15 after being passed through the slots 12, assume the form of a head, a more or less bulbous shape, carried by a restricted neck or stem 16'. This shape may, for want of a better term, be termed "dovetail", and it will be seen that the sides of the head are spaced for sufficient contraction under pressure. After the lugs are positioned in the slots as shown in Figure 5, the blank is then folded on the line B and

the two halves of the blank brought into contact and are held in that position by a cap or clamp 17 of any suitable material. The card is now in condition to receive, for display, artificial teeth. The artificial tooth 18 has a retention opening corresponding, more or less, to the cross section of the lugs 15 and they are slid on the lugs as shown in Figure 9. The marginal edges of this retention opening are thin and, if the tooth is removed from a lug of rigid type by pulling it transversely off the lug, instead of sliding it longitudinally off the lug, such edges are generally chipped or otherwise injured, thus seriously damaging the tooth.

After the card is filled with teeth of a certain shape and color, a card 19 is slipped in the folded blank and has indicia printed thereon, designating the shape and color of the teeth on the card, which indicia can be seen through the openings 11 in the blank.

The lugs 15 are characterized by the fact that they are more or less resilient and offer less resistance than the porcelain of the tooth and that, therefore, if one should pull a tooth from the card transversely or at any other angle to the longitudinal axis of the lug, the sides of the bulbous head of the lug and the head contact will readily yield with a reduction of its width so as to permit the tooth to be removed from the lug without any danger of spalling or chipping the tooth. As shown, each lug, comprising an engaging head and a restricted neck, as hereinbefore described, is substantially U-shaped, and the parts of the lug on opposite sides of its longitudinal center, therefore, form yielding or resilient jaws connected at their outer ends by the crossed part of the head. By forming the lug strip and each lug of a yielding non-metallic material, a tooth fitted on the lug, if removed by pulling it transversely off the lug, instead of sliding it longitudinally off the lug, will not be damaged, as the jaws of the lug will yield under pressure and thus contract the head, allowing the tooth to be released without chipping or otherwise injuring the marginal edges of its retention slot. As far as I know I am the first to provide such a yielding tooth supporting lug.

The thickness of the lug strip 14 spaces the two folded portions of the blank just sufficient to permit of the ready insertion and withdrawal of the indicia card 19, and the notches 13 expose the ends of the card 19 just enough to enable one to grasp its ends for removal.

The groove D and boss C serve two purposes: first, the groove holds the strip 14, and, second, the boss C raises the level of the supporting surfaces of the lugs, i.e., projects such surfaces outwardly beyond the plane of the card to such a degree that the tooth will pass over the metal cap 17 without friction.

What I claim is:

1. A carding device for artificial teeth

comprising a card of sheet material having a portion thereof displaced from its plane to provide a longitudinally extending boss at one side thereof and a corresponding groove at the opposite side thereof, the walls of the boss being provided at intervals with slots, and a tooth retaining strip of non-metallic material seated in said groove and doubled at intervals to provide yielding tooth receiving and supporting lugs projecting through said slots beyond the face of the boss.

2. A carding device for artificial teeth comprising a card of sheet material having a portion thereof displaced from its plane to provide a longitudinally extending boss at one side thereof and a corresponding groove at the opposite side thereof, the walls of the boss being provided at intervals with slots, and a tooth retaining strip of non-metallic material seated in said groove and doubled at intervals to provide yielding tooth receiving and supporting lugs projecting through said slots beyond the face of the boss, each lug comprising a stem portion forming yielding jaws and a head portion connecting said jaws.

3. A carding device for artificial teeth comprising a card of sheet material having a portion thereof displaced from its plane to provide a longitudinally extending boss at one side thereof and a corresponding groove at the opposite side thereof, the walls of the boss being provided at intervals with slots, and a tooth retaining strip of non-metallic material seated in said groove and doubled at intervals to provide yielding tooth receiving and supporting lugs projecting through said slots beyond the face of the boss, each lug comprising a stem portion forming yielding jaws and a head portion connecting said jaws, the head portion being of bulbous form in cross-section.

4. A carding device for artificial teeth comprising a card of sheet material doubled upon itself to provide a pair of corresponding leaves integrally connected at one edge, one of said leaves having a portion displaced from its plane to provide a longitudinally extending boss projecting beyond the outer face thereof and a corresponding groove in the inner face thereof, said boss being provided with slits at intervals, a clip engaging the free edges of the leaves to hold the same in folded condition, and a card retaining strip of non-metallic flexible material seated in the groove and doubled upon itself to provide tooth holding lugs projecting outwardly through the slots in the boss beyond the plane of said boss, the outer face of the boss lying in a plane beyond the plane of the clip.

5. In a carding device for supporting and displaying artificial teeth, a tooth card having a groove extending lengthwise thereof and slots extending from said groove through the outer face of the card, and tooth support-

ing lugs of fibrous material extending from said groove through said slots, and projecting beyond the outer face of the said card.

6. In a carding device for supporting and displaying artificial teeth, a tooth card having a groove in said card extending longitudinally thereof, and slots extending from said groove through the outer face of said card, a lug strip of cardboard or like fibrous material seated in said groove, and tooth supporting lugs formed by crimping said strip and projected through said slots and beyond the outer face of said card.

In testimony whereof I affix my signature.

15 DAVID E. EVANS.
